UNITED STATES PATENT OFFICE

IRENE M. LUKE, OF IRVINGTON-ON-HUDSON, NEW YORK

DESIGN FOR A COMBINED SET OF CONDIMENTS CONTAINERS AND HOLDER THEREFOR

Application filed July 2, 1931. Serial No. 40,400. Term of patent 14 years.

To all whom it may concern:

Be it known that I, IRENE M. LUKE, a citizen of the United States, residing at Irvington-on-Hudson, in the county of Westchester and State of New York, have invented a new, original, and ornamental Design for a Combined Set of Condiment Containers and Holder Therefor, of which the following is a specification, reference being had to the accompanying drawing, forming part thereof.

The figure is a perspective view of a condiment holder set embodying my new design.

The rear side of the article may be plain or the panels may be decorated, as illustrated on the front and side surfaces.

This article is usually sold as a unitary article, although the individual condiment containers may be separately removed from the holder.

I claim:

The ornamental design for a combined set of condiment containers and holder therefor, substantially as shown and described.

IRENE M. LUKE.
